UNITED STATES PATENT OFFICE.

EDWARD B. EICHLTZ, OF ST. LOUIS, MISSOURI.

DESIGN FOR A DOOR-SECURER.

SPECIFICATION forming part of Design No. 33,425, dated October 23, 1900.

Application filed August 23, 1899. Serial No. 728,244. Term of patent 7 years.

To all whom it may concern:

Be it known that I, EDWARD B. EICHLTZ, a citizen of the United States, residing at St. Louis, in the State of Missouri, have invented and produced a new and original Design for Door-Securers, of which the following is a specification, reference being had to the accompanying drawings, forming part thereof.

Figure 1 is a plan view of a lock, showing my design. Fig. 2 is an edge view of my design.

As shown in the drawings, my design consists of a base *d*, upon the upper face of which and at one end is a cylinder *h*. The base *d* is rectangular in shape and tapers slightly in its width toward its outer extremity, which said extremity is turned downwardly at right angles, the downwardly-turned portion being tapered to a transverse edge *e*. The lower face 20 of the base, with the exception of the down-turned end, continues in the same plane

throughout its entire length. Upon the upper face of the base is the cylindrical portion *a*, the under side of which connects with the upper face of the base *d* and is perfectly flat 25 and unbroken. The sides of the cylindrical portion *a* are perfectly smooth and possess no perforations or other irregularities. The upper face of the cylindrical portion is also perfectly smooth; but this face is not parallel to the long diameter of the base *d*, as is the under face, but instead it lies at an acute angle thereto.

Having thus described my invention, what I claim is—

The design for a door-securer as herein shown and described.

EDWARD B. EICHLTZ.
